Frank C. Fischer
ATTORNEY

UNITED STATES PATENT OFFICE.

JAMES J. SANFORD, OF NEWARK, NEW JERSEY.

SAW-FILING DEVICE.

1,290,667.

Specification of Letters Patent.

Patented Jan. 7, 1919.

Application filed September 19, 1917. Serial No. 192,060.

To all whom it may concern:

Be it known that I, JAMES J. SANFORD, a citizen of the United States, residing in the city of Newark, in the county of Essex and

5 State of New Jersey, have invented certain new and useful Improvements in Saw-Filing Devices, of which the following is a full, clear, and exact description, such as will enable others skilled in the art to which it pertains to make and use the same, reference being had to the accompanying drawings, and to numerals of reference marked thereon, forming a part of this specification.

This invention relates to new and useful 15 improvements in saw filing devices, the object being to provide improved means, whereby the angle of the file with reference to the saw may always be positively and accurately fixed, and thus any particular pitch 20 given to the teeth without variation, and to simplify the structure of the device, so as to render the same positive, yet effective in operation, simple and inexpensive in construction, and durable in use.

25 These objects I perform in the preferred embodiment of my invention, which I have illustrated in the accompanying drawings, to which reference is had, and in which similar reference characters indicate corresponding parts in the several views.

In the drawings,

Figure 1 represents a plan view of the device; and

Fig. 2 represents a side elevation, partly in 35 section, taken on lines $x-x$ of Fig. 1.

In the drawings, the vise is indicated in dotted lines, to one jaw of which is removably secured a support 1, preferably of sheet metal, provided with a guide-bar 2, preferably of rectangular cross-section and of the shape illustrated in the drawings. Between the front surface of the support 1 and the opposite jaw of the vise is clamped the saw to be filed, which is also indicated in dotted lines. Slidably located upon the guide-bar 2 is a sliding plate 3, the rear ends of which are bent downwardly as at 5, to form guides, designed to have sliding engagement with the top and rear surface of the guide-bar 2.

10 Secured to the under side of the sliding plate 3 are downwardly and outwardly extending guides 6, designed to have sliding engagement with the under surface of the guide-bar 2. These guides 6, of which two are employed, one on each end of the plate 3 and located directly below the downwardly bent

ends or guides 5, may be secured to the under side of the plate 3 in any desired or convenient manner, as for instance, by rivets 7 or the like.

60 Adjustably secured to the sliding plate 3 is a pivoted lever 8, upon which is slidably mounted the file holder 9. The forward end of the lever 8 is provided with a stud 10, designed to be received by one of a series of 65 apertures 11 formed in the front of the sliding plate 3 and by means of which the pivoted lever 8 can be adjusted as the kind of saw to be filed may require.

The file holder 9 is provided with a longitudinally arranged slot, by means of which the file holder is slidably secured to the lever 8.

70 The upper surface of the file holder 9 is recessed to receive the handle 12 of the file 13, said handle being removably secured to the file holder by means of a strap or yoke 14 and a clamping screw 15.

75 With this construction, the file holder 9 is operated by moving the same back and forth on the lever 8, while the sliding plate 3 is moved forward or backward on the guide-bar 2 to carry the file from one tooth to the next, as each tooth is filed.

80 It will thus be seen that I have provided a saw-filing device, in which when assembled, the possibility of the parts becoming separated by careless manipulation, has been reduced to a minimum. The parts are of such shape as to lend themselves readily to 85 manufacture by the use of suitable punches and dies from ordinary sheet metal.

85 Experience has demonstrated that the organization above described is a practical and efficient one for accomplishing the ends 90 sought by this invention. The construction may, however, be varied in detail by those skilled in such matters, without departing 95 from the scope of the appended claims.

100 I desire to claim the device as broadly as the art will permit and with no limitations other than such as may be expressed in the claims as they may be allowed.

I claim:

105 1. In a saw filing device, the combination with a support, designed to be secured to one jaw of a vise, a guide bar secured to and arranged parallel with said support, a plate provided with downwardly extending guides arranged near one end thereof designed to 110 have sliding engagement with the top and rear surface of the guide bar, guides secured

- to the underside of said plate designed to have sliding engagement with the under-surface of said guide bar, said plate being further provided with receiving means arranged near the front thereof, a lever pivotally secured to said plate, said lever being provided with holding means designed to engage with said receiving means arranged near the front of said plate for holding the lever in adjusted position, and a file holder provided with means for securing a file thereto, slidably arranged upon said lever.
2. In a saw filing device, the combination with a support, designed to be secured to one jaw of a vise, a guide bar secured to and arranged parallel with said support, a plate provided with downwardly extending guides arranged near one end thereof designed to have sliding engagement with the top and rear surface of the guide bar, guides secured to the underside of said plate designed to
- have sliding engagement with the under-surface of said guide bar, said plate being further provided with receiving means arranged near the front thereof, a lever pivotally secured to said plate, said lever being provided with holding means designed to engage with said receiving means arranged near the front of said plate for holding the lever in adjusted position, and a file holder slidably arranged upon said lever, by means of a longitudinally arranged slot in said holder, the upper surface of the file holder being recessed to receive the handle of a file and means embracing the file holder and file handle for clamping the same together.
- This specification signed and witnessed this 15th day of September, 1917.

JAMES J. SANFORD.
